UNITED STATES PATENT OFFICE.

BENJAMIN F. STEPHENS, OF NEW YORK, N. Y.

DESIGN FOR AN EYE-CUP.

SPECIFICATION forming part of Design No. 30,756, dated May 16, 1899.

Application filed March 27, 1899. Serial No. 710,712. Term of patent 14 years.

To all whom it may concern:

Be it known that I, BENJAMIN F. STEPHENS, a citizen of the United States, residing at New York, (Brooklyn,) in the county of Kings and State of New York, have invented and produced a new and original Design for an Eye-Cup, of which the following is a specification.

In the accompanying drawings, Figure 1 is a section, and Fig. 2 is an end view, of the eye-cup; and Fig. 3 is a perspective view illustrating the design of the eye-cup.

The leading feature of this design for an eye-cup relates to the interior shape and con-

figuration of the cup, the portion down to the line 2 being a concave globular segment of a larger radius than the concave portion at the bottom of the cup below the said line 2. The exterior of the cup is circular.

I claim—

The design for an eye-cup, substantially as described and shown.

Signed by me this 23d day of March, 1899.
BENJ. F. STEPHENS.
